UNITED STATES PATENT OFFICE.

CARL G. HILGENBERG, OF BALTIMORE, MARYLAND.

BOTTLE.

1,296,288.

Specification of Letters Patent.

Patented Mar. 4, 1919.

Application filed January 18, 1917. Serial No. 143,113.

To all whom it may concern:

Be it known that I, CARL G. HILGENBERG, a citizen of the United States, residing at Baltimore, in the State of Maryland, have invented a new and useful Bottle, of which the following is a specification.

This invention relates to bottles or other glass containers utilizing stoppers formed of glass or other hard material.

Heretofore, for certain commercial purposes, it has been the practice to grind stoppers into the necks of the bottles in which they are to be placed so that the stoppers will fit tightly within the necks, bottles of this character being especially desired in the high class, discriminating perfume trade where expensive perfumes are sold.

It is well known to those thoroughly acquainted with the art that bottles or other containers utilizing cork stoppers or glass stoppers with cork sleeves will be accepted by the public when purchasing inexpensive merchandise such as toilet water, hair tonic, etc., but when expensive perfumes are purchased, it has been found necessary, in order to meet the demands of the trade, to place the perfumes in bottles in which no cork is used.

To meet the requirements of the trade expensive machinery has been devised in order that stoppers may be ground into the necks of bottles, this operation being objectionable not only because of the expense involved in the purchase and operation of the machinery, but also because of the high wages which must be paid to skilled mechanics known in the trade as "grinders."

Aside from the objection to the use of ground stoppers, due to the high cost of production, it is well known that no two stoppers are of the same shape and, consequently, should a stopper inadvertently be placed in the wrong bottle neck, a tight joint would not be effected and leakage of the contents of the bottle would result. Serious losses are thus often occasioned and, in an effort to avoid such losses, it has been the practice to tie the stoppers to the bottles to which they belong, thereby adding to the cost of the bottles to the consumer.

One of the objects of the invention is to obviate the need of grinding stoppers in bottle necks but, at the same time, to provide means whereby molded glass stoppers can be fitted tightly in bottles without the use of cork or the like, without resulting in the use

of an unsightly container which will not be received by the discriminating trade, and which is not only cheaper to produce than the bottles using ground stoppers but is 60 less likely to result in leakage.

With the foregoing and other objects in view which will appear as the description proceeds, the invention resides in the combination and arrangement of parts and in the 65 details of construction hereinafter described and claimed, it being understood that changes in the precise embodiment of the invention herein disclosed, can be made within the scope of what is claimed, without 70 departing from the spirit of the invention.

In the accompanying drawings the preferred forms of the invention have been shown.

In said drawings:—

Figure 1 is a section through a portion of a bottle having the present improvements combined therewith, the stopper being shown seated in the bottle neck.

Fig. 2 is a section on line 2—2 Fig. 1. 80

Fig. 3 is a view similar to Fig. 1 and showing a modified arrangement of sealing means.

Referring to the figures by characters of reference 1 designates a portion of a bottle 85 or other container within the neck portion of which is formed an annular groove 2. In this groove is seated a ring 3 of lead or other soft material said ring projecting inwardly beyond the inner surface of the bottle neck 90 so as to be directly engaged by the tapered stopper 4 when inserted into the bottle neck.

In practice it is preferred to have that portion of the interior of the bottle neck above the groove 2 of slightly greater diameter than the remaining portion of the neck so that the bottom wall of the groove will thus project inwardly and form a ledge to support the metal ring 3 when it is first inserted downwardly into the bottle neck. 100 Then when the tapered stopper 4 is inserted into the ring and pushed downwardly it will expand the soft metal ring and force it radially into the groove 2 so as to pack tightly in the groove and at the same time frictionally engage the stopper. Thus leakage past the ring while the stopper is in place will be

prevented and the ring will grip the stopper with sufficient friction to prevent the stopper from being inadvertently removed. Consequently, although the stopper and the neck are not ground, the sealing of the bottle is 110

as efficient and the retention of the stopper is as positive as though the parts had been ground. Then too, even though the stopper should not fit accurately within the neck under ordinary conditions, it will shape the ring so as to fit snugly therearound no matter what its contour may be, thereby insuring against leakage.

The metal can be of such a color as to cause the neck to have practically the same appearance on the outside as would be the case should the interior of the neck be provided with a ground portion. Likewise should it be desired to protect the metal from some forms of acids it can be plated with nickel, silver or the like.

Instead of providing the metal ring within the neck of the bottle, it can be applied directly to the stopper as shown in Fig. 3. 20 By referring to this figure it will be noted that the neck of the bottle is slightly flared, as indicated at 5 and that the tapered stopper 6 has an annular groove 7 in which a ring 8 of lead or other soft metal is seated. 25 Thus when the stopper is forced into the flared end of the bottle neck, this metal ring will become packed within the groove 7 and will also frictionally engage the wall of the bottle neck, thus adapting itself to the 30 contour of said wall and serving both to prevent leakage and to hold the stopper tightly in position.

While the ring has been described and shown as seated in a groove, it is to be understood that if preferred said ring can engage a ledge projecting inwardly from the bottle neck or projecting outwardly from the stopper, this ledge being produced by removing the upper wall of the groove shown in Fig. 1 or the lower wall of the groove shown in Fig. 3.

What is claimed is:

1. The combination with a glass container

having a neck portion, of a stopper insertible into said neck portion and having a tapered portion, one of said portions having an annular groove, an inert soft metal ring slideable into position opposite the groove, and means for holding the ring in such position, said ring being adapted to be pressed into the groove during the first insertion of the stopper into the neck portion to form a permanent filling for the groove, said ring constituting a friction seal between the stopper and neck. 45

2. The combination with a glass container having a neck portion, of a stopper insertible into said neck portion and having a tapered portion, one of said portions having an annular groove provided with a protecting wall forming a ledge, an inert soft metal ring slideable into position against said ledge and adapted to be pressed into the groove during the first insertion of the stopper into the neck portion to form a permanent filling 60 for the groove, said ring constituting a friction seal between the stopper and neck. 65

3. The combination with a glass container having a neck, of a glass stopper insertible into the neck, said neck having an interior groove, the lower wall of the groove projecting inwardly beyond the upper wall therof to form a ledge, and an inert soft metal ring slideable into position against said ledge and adapted to be pressed into the groove during the first insertion of the stopper into the neck portion, said ring constituting a friction seal between the stopper and neck. 70

In testimony that I claim the foregoing as my own, I have hereto affixed my signature in the presence of two witnesses.

CARL G. HILGENBERG.
